UNITED STATES PATENT OFFICE.

EDWIN LE SUEUR POWELL, OF NEW ORLEANS, LOUISIANA, ASSIGNOR TO AMERICAN CREOSOTE WORKS, A COPARTNERSHIP CONSISTING OF SYLVESTER W. LABROT, EDWIN L. POWELL, WILLIAM S. BRYAN, AND JOHN M. VAN DERVEER.

PRESERVED TIMBER AND METHOD OF MAKING SAME.

1,151,039.

Specification of Letters Patent. Patented Aug. 24, 1915.

No Drawing.

Application filed May 9, 1912. Serial No. 696,267.

To all whom it may concern:

Be it known that I, EDWIN L. POWELL, a citizen of the United States, residing at New Orleans, in the parish of Orleans and State 5 of Louisiana, have invented certain new and useful Improvements in Preserved Timber and Methods of Making Same; and I do declare the following to be a full, clear, and exact description of the invention, such as 10 will enable others skilled in the art to which it appertains to make and use the same.

The object of my present invention is the production of timber, particularly piles, which shall be fully preserved for a part 15 only of their length, that is, at the part, or parts where they are subject to decay or to the action of insects, teredo, liminoris, or fungus, etc.

These results I accomplish in the manner 20 set forth below.

This invention relates to the preservation of unsawn timber, such as piles, telephone poles, posts, etc., particularly of such woods as Southern yellow pine, etc., which wood 25 has, inside its bark a sort of thin inner bark, commonly referred to as "skin" since it is in the form of a thin reddish brown skin which adheres very closely to the wood. Now this skin, is practically impervious to 30 creosote and similar preservatives and if wood is to be wholly impregnated this skin must be removed. It has heretofore been proposed to impregnate piles, poles, etc., for a part only of their length, and for many 35 purposes this is advisable.

Now my present invention consists in the preservation of poles, piles, etc., through a part of their length by first removing the outer bark, if desired, from the entire length 40 of the stick, and removing the skin, or inner bark (substantially completely) from only that part of the length which it is desired to impregnate, and then treating the entire stick of wood with the oil, under the usual 45 or any preferred conditions of heat, vacuum, pressure, etc.

Wood does not decay in that part which is permanently in wet soil, but the part in salt water is subjected to the destructive 50 action of animals,—marine borers—and the part above the water line, and also the part which is alternately wet and dry, is subject to decay and fungous growth, dry rot, etc.

Wood constantly submerged in fresh water does not suffer much from decay or insect 55 life. Accordingly it is necessary to creosote piling to be used in fresh water only in that part from say two feet below low water mark up to the top of the pile while in the case of piling to be used in salt water the 60 wood should be impregnated from a point say four feet below the mud line to the top of the pile. Heretofore all piling used in this country, which has been creosoted at all has been treated the full length and on 65 account of the fact that the small end or top of the tree (as it grows) contains a much larger percentage of sap wood than the butt, the end of the pile which goes into the ground has a much greater amount of 70 oil, per cubic foot, than the butt, or in other words the part of the stick requiring no preservative gets the greatest amount of preservative fluid.

Now by my improved process, substantially 75 no oil is used to impregnate that part of the wood which does not require preservation, the small amount absorbed apparently entering through small breaks or cuts accidentally made in the inner bark or 80 "skin."

It is preferable to remove all the "skin" from that part of the length which it is desired to fully impregnate, but small pieces, say not greater than an inch wide by five 85 or six inches long will not prevent substantially complete impregnation at these points.

Any desired method of impregnation may be employed, open cell, full cell, impregnation clear to the heart or more superficial, 90 as desired.

It is also obvious that certain other kinds of wood, beside Southern yellow pine may have an inner bark similar to that described for this kind of wood, and my invention also 95 includes the preservation of such woods.

Obviously other preservatives beside creosote may be employed.

Having described my invention, what I 100 claim is:—

1. A stick of timber having the outer bark removed therefrom, and having the inner bark removed from a portion only of its length, and having said portion impregnated with a preservative.

2. A pile having the outer bark removed 105

therefrom, and having the inner bark removed from a portion of its length near the end having the larger diameter, and having said portion impregnated with a preservative.

5 3. A stick of timber having the outer bark removed therefrom throughout substantially its entire length; and having the inner bark on a portion of its length, and having another portion of its length impregnated with a preservative.

10 4. A process of impregnating a portion of the length of a stick of timber, which comprises removing the outer bark from substantially the entire length of the stick and removing the inner bark from a portion of the length of said stick, then treating with a preservative, under conditions whereby the portion from which the bark is removed becomes impregnated with the preservative.

15 5. Yellow pine piling, having the outer bark removed therefrom, throughout substantially its entire length and having the inner bark removed from a portion of its length adjacent the end of larger diameter, and having the inner bark left on the remainder of its length, said end of larger diameter being impregnated with a preservative.

20 6. Yellow pine piling, having the outer

bark removed therefrom, throughout substantially its entire length and having the inner bark removed from a portion of its length adjacent the end of larger diameter, and having the inner bark left on the remainder of its length, said end of larger diameter being impregnated with a preservative oil.

25 7. Yellow pine piling, having the outer bark removed therefrom, throughout substantially its entire length and having the inner bark removed from a portion of its length adjacent the end of larger diameter, and having the inner bark left on the remainder of its length, said end of larger diameter being impregnated with creosote oil.

8. A process of preserving wood which comprises the removal of the outer bark and leaving on a portion only of the length of the wood a material which will substantially prevent entrance of a preservative liquid, and impregnating the wood with a preservative.

30 In testimony whereof I affix my signature in presence of two witnesses.

EDWIN LE SUEUR POWELL.
